UNITED STATES PATENT OFFICE.

HARRY SUTHANN, OF MIDDLETOWN, OHIO.

INGOT-MOLD.

1,243,779.

Specification of Letters Patent. Patented Oct. 23, 1917.

Application filed July 30, 1915. Serial No. 42,718.

To all whom it may concern:

Be it known that I, HARRY SUTHANN, a citizen of the United States, residing at Middletown, in the county of Butler and State of Ohio, have invented certain new and useful Improvements in Ingot-Molds, of which the following is a specification.

My invention relates to improvements in ingot molds and refers more particularly to mold constructions for the purpose of preventing piping and the formation of blow holes in steel ingots.

In attempting to meet the conditions which produce these difficulties, various structure and molds have been employed involving generally an attempt to provide a forced action upon the molten metal through action upon the mold itself. For instance, it has been proposed to retain the top of the molten metal in the mold in fluid state by conserving the heat at this portion of the mold through the use of a cap, but such arrangement necessarily affects the escape of the deoxidized gases, since the exit of such gases is restricted.

It has also been proposed to provide a rapid cooling action at the lower end of the ingot through the use of a cooling agent within the lower portion of the mold and conserving the heat at the upper end, thus increasing the rapidity of the cooling action within that portion of the ingot in which piping does not generally form and enabling the molten metal at the top of the ingot to move downwardly as contraction takes place at the lower end.

In both these forms of apparatus, the purpose is to vary the heat radiation provided by the mold, the differences between the two forms being in increasing the variation in the latter form. These solutions of the difficulties are presumably based upon the premises that the portion of the molten metal in contact with the mold walls solidifies with much greater rapidity than the interior, thereby tending to form the exterior of the ingot in its complete structure so far in advance of the solidifying of the interior as to cause such outer solidified portion to prevent any downward movement to correspond with the downward movement of the central portion as the mass solidifies.

In the present invention, I aim to greatly reduce, if not entirely overcome, this tendency of forming a piping or the blow holes,

by conserving the heat of the mold walls practically throughout the length of the mold, thereby preventing as far as possible material chilling action on the contacting portions of the molten metal and the mold walls, thus tending to materially extend the time of solidification along such walls and thereby permit the metal to solidify in a normal and gradual manner, so that the solidification more nearly approaches uniformity, and at the same time, permit of the escape of the deoxidized gases and practically prevent the entrance of oxygen. Although this action has the effect to increase the length of time required in solidification, this effect is overcome by reason of the fact that wastage of ingot is greatly reduced or eliminated by reason of the reduction or absence of piping. At the same time, the free release of the gases tends to prevent the formation of blow holes within the ingot, the solidifying action taking place at a reduced speed.

A further aim is to provide an ingot mold of simple type and which can be manufactured at relatively low cost.

To these and other ends, the nature of which will be readily understood as the invention is hereinafter disclosed, said invention consists in the improved construction and combination of parts hereinafter fully described, illustrated in the accompanying drawings, and more particularly pointed out in the appended claims.

In the drawing,

Figure 1 is a side elevation of a mold constructed in accordance with my invention.

Fig. 2 is an elevation at right angles to Fig. 1, with parts broken away to indicate the sectional construction.

Fig. 3 is a horizontal cross sectional view.

The ingot mold of the present invention is similar in general structural characteristics to the type of mold usually employed for this purpose, being in the form of an open-ended mold, the inner mold walls slightly tapering toward the bottom of the mold to facilitate the stripping action. The walls of the mold, however, in the present invention, are increased in thickness over those usually employed, this increase being provided to enable cavities to be formed therein, these cavities being adapted to receive refractory material.

In the drawing, the mold generally is indicated at 10 and the cavities at 11, the latter being arranged in each of the walls of the mold, as shown more particularly in Fig. 3, the cavities extending from the top of the mold to a point adjacent the mold bottom plane, as shown in Figs. 1 and 2, the cavities being of sufficient width to provide a material thickness to the layer of refractory material which is located therein. For instance, a suitable construction is to provide a wall thickness of five and one-half inches, a cavity width of two inches, with the inner plane of the cavity spaced approximately two inches from the inner plane of the wall. This gives an efficient heat insulating arrangement with a sufficient body of material between the insulating layer and the molten metal to provide the desired results.

While the cavities are necessarily closed at their lower ends, this does not materially affect the desired operation, since the molds are arranged on stools which extend into the lower end of the mold.

Any desired refractory material may be employed in the cavity, a preferred material being crushed silica brick, this being a material which will not fuse under the high heats while maintaining the heat insulating effects.

As will be understood, the height of the lining or filler within the mold wall may depend upon the height of the molten metal within the mold. The fact that the cavities are open at their tops, enables an addition of lining material to be made at any time, and also permits of a change in the refractory material by removing the material through such open top.

By arranging the mold walls in this manner, radiation of heat from the walls is restricted, thus retaining the portion of the wall between the lining and the molten metal at higher temperatures during the solidifying period. Furthermore, the material of the mold wall between the lining and the molten metal is of a reduced thickness which enables it to reach the higher temperatures much more rapidly, so that the tendency to solidify on the surface of the

ingot through chilling action when contacting with the mold is reduced.

As will be obvious, solidification of the ingot takes place at a reduced speed, thereby permitting the deoxidized gases to freely pass out of the mold, and permit the molten metal to take care of the contraction effect in a more uniform manner.

What I claim is:—

1. An ingot mold having an open top and bottom and having a plurality of longitudinal cavities extending parallel with the interior surfaces of the mold wall, said cavities extending from the top plane of the mold to a point adjacent the bottom thereof and acting to produce inner and outer wall portions approximating the active length of the mold, with said inner and outer walls connected at predetermined points, said cavities being adapted to receive heat insulating material, whereby said walls will be substantially insulated from each other but connected sufficiently to permit heat conductive relation therebetween to a limited extent.

2. An ingot mold having an open top and bottom and having a plurality of longitudinal cavities extending parallel with the interior surfaces of the mold wall, said cavities extending from the top plane of the mold to a point adjacent the bottom thereof and acting to produce inner and outer wall portions approximating the active length of the mold, with said inner and outer walls connected at predetermined points, said cavities being adapted to receive heat insulating material, whereby said walls will be substantially insulated from each other but connected sufficiently to permit heat conductive relation therebetween to a limited extent, a cross section of the mold walls having its internal contour non-circular, said connections between walls being located at points where heat conduction is least effective on the ingot.

In testimony whereof I affix my signature in presence of two witnesses.

HARRY SUTHANN.
